To all whom it may concern:

Be it known that I, Joseph A. In the drawing, Fig. 1 is a plan view and Fig. 2 a section on the line 2—2 of Fig. 1 of the metal border strip showing my new design.

The dominant feature of the design resides in the intertwining of branches, leaves and cones of spruce and other coniferous trees in the form of a continuous strip, a complete repeat unit being shown in Fig. 1.

I claim:—

The ornamental design for a metal border strip for hollow ware, substantially as shown and described.
